UNITED STATES PATENT OFFICE

FRANK FORREST FULLER, OF ELIZABETH, NEW JERSEY

AUTOMATIC PILING LUBRICATOR

Application filed March 22, 1930. Serial No. 438,211.

This invention relates to lubricators, and has for one of its objects to provide a novel, simple and highly efficient device of this character which shall be adapted to be used for the purpose of lubricating piling, fender boards and guard rails and which shall be adapted to be applied to a ferry boat, tug boat, car float or any other water craft in a manner to effect the automatic lubrication of the parts stated when the craft is coming into port and immediately prior to contact with the piling.

With the foregoing and other objects in view, the nature of which will appear as the description proceeds, the invention consists in the construction, combination and arrangement of parts hereinafter fully described and claimed, and illustrated in the accompanying drawings, wherein:—

20 Figure 1 is a view in side elevation of the lubricator applied to a water craft:

Figure 2 is a sectional view on an enlarged scale taken on the horizontal plane indicated by the line 2—2 of Figure 1, and

25 Figure 3 is a sectional view on an enlarged scale taken on the vertical plane indicated by the line 3—3 of Figure 2.

Referring in detail to the drawings, 1 designates the guard rail, 2 the outside wall, 30 and 3 the upper deck of a ferry boat, these parts being shown in order to illustrate the manner in which the lubricator is adapted to be applied to a boat of this type. While the lubricator is shown as applied to a ferry boat, it is to be understood that it is adapted to be applied to a water craft of any other type.

The lubricator comprises a pump 4 which embodies a cylinder 5 and a solid reciprocating piston 6. The cylinder 5 is carried by a base plate 7 which is mounted upon the guard rail 1 and is secured thereto by bolts 8. The cylinder 5 extends transversely of the guard rail 1, and its outer end is spaced inwardly from the outer edge of the guard rail. The cylinder 5 is preferably formed integrally with a base plate 7, and also formed integrally therewith and with the cylinder are apertured lugs 9 which extend

upwardly from the base plate and radially from the cylinder.

The piston 6 extends through the outer end of the cylinder 5 and is provided at its outer end with a screw threaded stud 10. A bumper bar 11 is provided at a point centrally between its ends with a screw threaded socket 12 which opens through the inner side of the bumper bar and is engaged with the stud 10. Bolts 13 which slidably pass through the openings 14 of the lugs 9, have their outer ends screw threadedly engaged, as at 15, with the bumper bar 11, and have their heads 16 arranged at the inner sides of the lugs. The bolts 13, which are located at opposite sides of the piston 6, cooperate with the piston to support the bumper bar 11 in a parallel or substantially parallel position with respect to and above the guard rail 1, and these parts also hold the bumper bar against any turning movement about the longitudinal and transverse axes of the cylinder 5.

The bumper bar 11 constitutes an actuating member for the piston 6, and its outer side normally extends outwardly beyond the outer edge of the guard rail 1. The bumper bar 11 is held in this position with respect to the outer edge of the guard rail 1 by coil springs 17 which are mounted upon the bolts 13 between the guard rail and the lugs 9. The heads 16 of the bolts 13 cooperate with the lugs 9 to limit the outward movement of the bumper bar 11 under the influence of the spring 17. When the bumper bar 11 is in this position, the piston 6 is at the limit of its outward stroke. The terminal portions of the outer side of the bumper bar 11 are rounded, as at 11a.

A distributing pipe 18 is mounted upon the guard rail 1 close to and in parallel relation with the outer edge of the rail and is provided at intervals in the length thereof with spraying nozzles 19. The pipe 18 may be secured by clips 20 or in any other suitable manner to the guard rail 1, and it is closed at its ends. The nozzles 19 extend downwardly and outwardly from the pipe 18, and are provided at their outer ends with discharge ports 21. The nozzles 19 are pro-

vided with spring controlled check valves 22 which seat inwardly to prevent air from being drawn into the pipe 18 by way of the nozzles. A pipe 23 extends from the rear end of the cylinder 5 to a point intermediate the length of the distributing pipe 18 to permit lubricant to be forced from the cylinder into the distributing pipe by the inward strokes of the piston 6. The pipe 23 is provided with a spring controlled check valve 24 which seats in the direction of the cylinder 5 to prevent lubricant from being drawn from the pipe into the cylinder during the outward strokes of the piston 6.

15 The lubricant is carried in a reservoir 25 which may be supported from the upper deck 3 by brackets 26 or in any other suitable manner. The lubricant is conveyed from the reservoir 25 to a chamber 27 by a pipe 28 which is provided with a cut-off valve 29. The chamber 27 is secured, as at 30, to the rear end of the cylinder 5, and is provided in its front side with an opening by which communication between the chamber and cylinder is established. The wall of this opening is beveled to provide a seat 31 for the valve 32 which opens in the direction of the cylinder to permit the lubricant to be drawn into the latter during the outward strokes 30 of the piston 6. The valve 32 is carried by a rod 33 which is slidably mounted in a guide 35 carried by the outer side of the chamber 27. A coil spring 36 which surrounds the rod 33 between the inner side of the chamber 27 and a stop 37 carried by the inner end of the stem, serves to yieldingly hold the valve 32 against its seat 31. A housing 38 for the outer end of the valve stem 33 and spring 36 is secured, as at 39, to the inner side of the chamber 27.

As it extends outwardly beyond the guard rail 1 of the craft, the bumper bar 11 will contact with piling when the craft is coming into port and immediately before the guard rail contacts with the piling, with the result that it will be moved inwardly against the tension of the spring 17. This movement of the bumper bar 11 will impart an inward stroke to the piston 6, with the result that the lubricant in the cylinder 5 will be forced therefrom into the pipe 18 by way of the pipe 23, the lubricant spraying out of the nozzles 19 onto the guard rail and piling in sufficient quantity to effect the lubrication of such parts.

When the force acting against the bumper bar 11 to force it and the piston 6 inwardly ceases to act, the springs 17 will react and force these parts outwardly, with the result that a fresh supply of lubricant is drawn into the cylinder 5. During the outward strokes of the piston 6, the valves 22 and 24 seat to prevent air from being drawn into the cylinder 5, and the valve 32 unseats to permit the lubricant to be drawn into the cylinder.

During the inward strokes of the piston 6, the valve 32 seats to prevent the lubricant from being forced from the cylinder 5 into the chamber 27, and the valves 24 and 22 unseat to permit the lubricant to be forced from the cylinder and out through the nozzles 19 by way of the pipes 23 and 18. To permit it to be primed or initially charged with a supply of lubricant, the cylinder 5 is provided with an air vent 40.

While I have described the principle of the invention, together with the structure which I now consider the preferred embodiment thereof, it to be understood that the structure shown is merely illustrative and that such changes may be made, when desired, as fall within the scope of the invention as claimed.

I claim:—

1. A device adapted to be carried by a water craft for automatically lubricating piling, comprising a cylinder adapted to be mounted on the craft, means adapted to supply lubricant to the cylinder, means in communication with the cylinder and adapted to apply the lubricant to the piling, a piston in the cylinder, and means adapted to cooperate with the piling to effect the operation of the piston in a direction to force the lubricant from the cylinder to said second means. 95

2. A device adapted to be carried by a water craft for automatically lubricating piling, comprising a cylinder adapted to be mounted on the craft, means adapted to supply lubricant to the cylinder, a distributing pipe in communication with the cylinder, nozzles in communication with the distributing pipe, a piston in the cylinder, and means adapted to cooperate with the piling to effect the operation of the piston in a direction to force the lubricant from the cylinder into the distributing pipe and from the distributing pipe through the nozzles. 100

3. A device adapted to be carried by a water craft for automatically lubricating piling, comprising a cylinder adapted to be mounted on the craft, means adapted to supply lubricant to the cylinder, a distributing pipe, a pipe establishing communication between the cylinder and distributing pipe and provided with a check valve seating in the direction of the cylinder, nozzles communicating with the distributing pipe and provided with check valves seating in the direction of the distributing pipe, a piston in the cylinder, and means adapted to cooperate with the piling to move the piston in a direction to force the lubricant from the cylinder into the distributing pipe and from the distributing pipe through the nozzles. 110

4. A device adapted to be carried by a water craft for automatically lubricating piling, comprising a cylinder adapted to be mounted on the craft, a chamber communicating with the cylinder, means adapted 120

to supply lubricant to the chamber, a spring seated valve controlling communication between the chambers and cylinder and opening in the direction of the latter, means in communication with the cylinder and adapted to supply the lubricant to the piling, a piston in the cylinder, and means adapted to cooperate with the piling to move the piston in a direction to force the lubricant from the cylinder to the applying means.

5 10 5. A device adapted to be carried by a water craft for automatically lubricating piling, comprising a cylinder adapted to be mounted on the craft, means adapted to supply lubricant to the cylinder, means in communication with the cylinder and adapted to apply the lubricant to the piling, a piston in the cylinder, a bumper bar secured to the piston, and springs interposed between the 15 20 cylinder and bumper bar.

6 25 6. A device adapted to be carried by a water craft for automatically lubricating piling, comprising a cylinder adapted to be mounted on the craft, means adapted to supply lubricant to the cylinder, means in communication with the cylinder and adapted to apply the lubricant to the piling, a piston in the cylinder, a bumper bar secured between its ends to the piston, lugs carried by the cylinder, bolts carried by the upper bar slidably through the lugs, springs mounted on the bolts between the bumper bar and lugs, and stop elements carried by the bolts and contacting with the lugs.

30 35 7. A device adapted to be carried by a water craft for automatically lubricating piling, comprising a pump adapted to be mounted on the craft, pump operating means projected beyond the craft, means for supplying lubricant to the pump, and means adapted to supply the lubricant to the piling and communicating with the pump.

40 In testimony whereof I hereunto affix my signature.
